UNITED STATES PATENT OFFICE

GERHARD KARL EMIL HEINRICH STAMPE, OF LUBECK, GERMANY

RESPIRATING IMPLEMENT BAG

Application filed October 2, 1928, Serial No. 309,859, and in Germany October 11, 1927.

The present invention relates to improvements in wrappers for the filling material of gas protecting and breathing cartridges.

For protecting the breathing organs in rooms, the contents of which comprise but a small percentage of noxious gases of not very poisonous character, frequently light gas protecting implements are used instead of the heavy and comparatively expensive gas 10 masks having a metallic filter-cartridge. Such implements were constructed originally only for the protection against dust, and contained for this purpose as air filtering means a layer or pad of cotton-wool or similar material generally disposed in a cylindrical chamber or container. In order to adapt such chamber for other filtering means serving as a protective means against poisonous gases, special arrangements will be necessary, for 20 example perforated sheet-metal cans or tins, which receive the filtering material and are to be placed into the said cylindrical chambers. Devices of this kind, however, materially increase the costs of the filter implement.

25 The most simple and cheapest way for accommodating the filling mass of air-filters in a special wrapper would be to make use of a small bag or pouch of textile fabrics. Since, however, the filling mass, as a rule, has a 30 granular form or comprises small lumps, such a small bag would have the drawback that its shape will easily be submitted to changes. Therefore it cannot be warranted that such a bag will at all times entirely fill up the 35 cross-sectional area of the air passage through the cartridge casing, and particularly after lengthy use will retain such shape as it will require for answering its purpose.

By stiffening various places or portions of 40 such bags, the retention of the desired shape of the bag will be assured and the present invention relates to the manufacture of such textile bags, and more particularly to the 45 manner of stiffening or solidifying them in the desired places by applying a substance adapted to become stiff, or by impregnating the desired places with a solution of such a substance. The price of the bags will not be materially increased by such procedure, 50 whilst the above mentioned drawback of the

possibility of being easily deformed is obviated. According to the invention each bag is manufactured conveniently of two or more parts or pieces to be glued together, the glued faces forming the stiffenings. Taking this 55 for granted the working stage of manufacturing the said bags suffices to give them also the desired shape and stiffness. Such a small bag may consist, for example, of a hose-like part and a bottom-part or disk provided with 60 an upright rim or flange. By gluing together the lower end of the hose-part and the said flange of the bottom-part there is accomplished at this zone of gluing a circular stiffening ring which fits snugly, for example, 65 into the cylindrical inner wall of the cartridge casing thereby avoiding detrimental leakages between the bag and the casing. As flexible porous material for the said small 70 bags, an artificial silk-tissue may be chosen 75 preferably, and as a glue and stiffening means, collodion or a similar solution are found to be well adapted. The gluing together of artificial silk by means of collodion or a similar solution will be equivalent to a 80 welding operation in that the separate threads are superficially dissolved by the dissolving means of the glue and the binding means of this glue consists of the same material as the fibre itself. Owing to the equality of these materials, sewing stitches, if any, 85 in the bags may be easily closed mechanically by lacquering them with nitrocellulose or a cellulon-lac. A special advantage of the manufacture of the small bags of artificial silk 90 consists furthermore in that the latter, owing to the smooth surface of the textile fibres, exerts only a very slight absorbing power upon the gases passing through them during the breathing operation and also upon the liquids with which the filter-devices are impregnated. The said bags may also easily be 95 washed and cleansed.

The inventive idea upon which the invention is based, may be carried into practice in 95 every suitable manner.

In the drawing is shown as an example an embodiment of the invention.

According to Fig. 1 the bag is to be composed of a hose-like part 1 and a bottom part

or disk 2 having an upright rim or flange 3. The latter and the lower end of the part 1 are glued together in order to form after their union a small bag or pouch the zone of 5 connection or gluing of which forms a shaping and stiffening ring. After filling the filtering material into the bag the upper opening of the same is closed. This may be effected either according to Fig. 2 by lacing 10 tightly the upper end of the bag by means of a sack-string 5, or according to Fig. 3 by gluing a patch of fabric 6 over the upper opening of the bag, as shown.

I claim:—

- 15 1. The combination of a charge of filling material of the type employed in gas protecting and breathing cartridges, and a wrapper of porous textile fabric surrounding said filling material, said wrapper having stiffened portions, the stiffened portions being adapted to sustain the general shape of the package formed by the filling material and wrapper.
- 20 2. A structure as defined in claim 1, wherein the wrapper comprises a plurality of parts, and adhesive material connecting said parts; the joints formed at said connection constituting the stiffening.
- 25 3. The combination of a charge of filling material of the type employed in gas protecting and breathing cartridges, a wrapper of porous textile fabric comprising a plurality of parts surrounding said filling material, and collodion connecting said parts.
- 30 4. A structure as defined in claim 1 wherein the wrapper comprises, an upper portion constituting side walls and a top, a lower portion comprising a base provided with an upright flange engaging the side walls of the upper portion, and adhesive material connecting the upright flange with the side walls of the upper portion.

In testimony whereof I have signed my name to this specification.

45 GERHARD KARL EMIL HEINRICH STAMPE.
